(57) **CLAIM**

The ornamental design for a refillable hand-held paint sprayer, as shown and described.

DESCRIPTION

FIG. 1 is a perspective view from the upper left front refillable hand-held paint sprayer including a first embodiment of my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and

FIG. 7 is a bottom plan view thereof; and in which

FIG. 8 is a perspective view from the upper left front of a refillable hand-held paint sprayer including a second embodiment of my new design;

FIG. 9 is a front elevational view thereof;

FIG. 10 is a left side elevational view thereof;

FIG. 11 is a right side elevational view thereof;

FIG. 12 is a rear elevational view thereof;

FIG. 13 is a top plan view thereof; and,

FIG. 14 is a bottom plan view thereof.

Portions of the refillable hand-held paint sprayer are shown in broken line in FIGS. 8-14 and are included merely for illustrative purposes and form no part of the claimed design. The broken lines represent unclaimed boundaries of the design.
